FAUCET FOR A BEVERAGE DISPENSER OR THE LIKE

Harold O. Seltsam, Rocky River, Ohio, assignor to Tomlinson Industries, Inc., Cleveland, Ohio, a corporation of Ohio

Filed May 23, 1960, Ser. No. 60,690

Term of patent 14 years

(Cl. D2—3)

FIG. 1

FIG. 2

FIG. 4

Fig. 1 is a perspective view of a faucet for a beverage dispenser or the like, showing my new design;

Fig. 2 is a side elevation;

Fig. 3 is a rear elevation; and

Fig. 4 is a top plan view thereof.

I claim:

The ornamental design for a faucet for a beverage dispenser or the like, as shown.
